UNITED STATES PATENT OFFICE

163,561

ADVERTISING SIGN

Kenneth E. Bemis, Washington, D. C.

Application August 2, 1950, Serial No. 11,549

Term of patent 14 years

(Cl. D1—12)

To all whom it may concern:

Be it known that I, Kenneth E. Bemis, a citizen of the United States, residing at Washington, D. C., have invented a new, original, and ornamental Design for Advertising Sign, of which the following is a specification, reference being had to the accompanying drawing, forming a part thereof, wherein:

Fig. 1 is a front elevation of an advertising sign, showing my new design;

Fig. 2 is a top plan view of the sign shown in Fig. 1; and

Fig. 3 is a cross sectional view of the advertising sign taken on the line 3—3 of Fig. 2.

The broken lines shown in Figs. 1 and 3 are for illustrative purposes only.

I claim:

The ornamental design for an advertising sign, as shown and described.

KENNETH E. BEMIS.
